US00D783215S

(12) **United States Design Patent** (10) **Patent No.:** **US D783,215 S**
(45) **Date of Patent:** **** Apr. 4, 2017**

(54) **STRING MOP HEADBAND**

- (71) Applicant: **Rubbermaid Commercial Products, LLC**, Winchester, VA (US)
- (72) Inventor: **Donald C. Presnell**, Stephens City, VA (US)
- (73) Assignee: **Rubbermaid Commercial Products, LLC**, Winchester, VA (US)
- (**) Term: **15 Years**
- (21) Appl. No.: **29/572,264**
- (22) Filed: **Jul. 26, 2016**

Related U.S. Application Data

- (62) Division of application No. 29/506,754, filed on Oct. 20, 2014, now Pat. No. Des. 765,931.
- (51) **LOC (10) Cl.** **04-01**
- (52) **U.S. Cl.** **D32/50**
- (58) **Field of Classification Search**

Primary Examiner — John Windmuller

Assistant Examiner — John R Yeh

(74) *Attorney, Agent, or Firm* — Eversheds Sutherland (US) LLP

(57) **CLAIM**

I claim the ornamental design for a string mop headband, as shown and described.

DESCRIPTION

FIG. 1 is a perspective view showing my new design for a string mop headband;

FIG. 2 is a front view showing my new design shown in FIG. 1;

FIG. 3 is a back view showing my new design shown in FIG. 1;

FIG. 4 is a left side view showing my new design shown in FIG. 1;

FIG. 5 is a right side view showing my new design shown in FIG. 1;

FIG. 6 is a top view showing my new design shown in FIGS. 1; and,

FIG. 7 is a bottom view showing my new design shown in FIG. 1.

1 Claim, 5 Drawing Sheets
